R. T. HOSKING,
SAFETY LOCK FOR COIN ACTUATED MACHINES.
APPLICATION FILED JUNE 16, 1917.

1,260,997.

Patented Mar. 26, 1918.

UNITED STATES PATENT OFFICE.

RICHARD T. HOSKING, OF SAGINAW, MICHIGAN, ASSIGNOR TO AMERICAN BANKING MACHINE CORPORATION, OF SAGINAW, MICHIGAN, A CORPORATION.

SAFETY-LOCK FOR COIN-ACTUATED MACHINES.

1,260,997.

Specification Letters Patent. Patented Mar. 26, 1918.

Application filed June 18, 1917. Serial No. 175,116.

To all whom it may concern:

Be it known that I, RICHARD T. HOSKING, a citizen of the United States, residing at Saginaw, in the county of Saginaw and State of Michigan, have invented certain new and useful Improvements in Safety-Locks for Coin-Actuated Machines; and I do hereby declare the following to be a full, clear, and exact description of the invention, 10 such as will enable others skilled in the art to which it appertains to make and use the same.

This invention relates to coin-actuated machines and pertains more particularly to 15 a safety lock or guard adapted to be applied to coin-actuated vending machines to prevent fraudulent delivery of goods or stamps from the machine.

The invention relates more especially to 20 coin-actuated stamp vending machines of the type shown in my Patent No. 1,163,012, issued December 7, 1915, which comprises a coin-stacking tube or receptacle, in which coins are inserted by a manually operated 25 feeding-in slide, the slide being suitably connected to a stamp delivery mechanism by which the stamp is delivered from the machine after a coin has been deposited by the slide and during the return movement of the 30 slide.

In my co-pending application, Serial No. 779,420, filed July 17, 1913, I have shown and described a device to prevent the feeding-in slide being pushed in far enough to 35 actuate the vending wheel unless a coin is being carried by the slide. This device comprises a latch pivotally mounted upon a stationary member of the frame of the machine. The latch has its lower edge provided with a stop and also carries a downwardly projecting central beveled tooth.

When a coin is on the slide and is being carried toward the receptacle, the advancing edge of the coin engages the beveled end of 45 the tooth and lifts the latch, the coin and slide passing under the lower edge of the tooth.

When there is no coin in the slide the tooth will not be engaged and the slide will 50 strike against the stop and prevent further forward movement of the slide.

If, however, the latch is first lifted, either accidentally or intentionally, so that the beveled tooth of the latch is raised clear of the 55 advancing slide, although there may be no

coin in the slide, it can be pushed in to the end of its travel, with the result that when the slide returns the stamp vending mechanism will be operated to deliver a stamp without having deposited a coin.

To prevent the latch from being lifted and held in its raised position, either accidentally, as by friction or binding of its pivot, or intentionally, as by a wire inserted into the machine to lift the latch and hold it 60 in its raised position, I provide the safety lock or guard which forms one subject-matter of my present invention and which will now be described.

It will be understood that for the purpose 70 of this present application any suitable stamp delivering device (not shown) may be actuated by the coin feeding-in slide, and that the mechanical connections between the feeding-in slide and the stamp delivering 75 mechanism will not operate to deliver a stamp unless the slide, carrying a coin of proper size, has been first pushed in to its full extent and then retracted by a spring or otherwise. I prefer, however, to use the 80 stamp delivery mechanism shown and described in the above-mentioned application, or the equivalent thereof.

The invention consists in the devices described and claimed and the equivalents 85 thereof.

In the drawings, Figure 1 is a top plan view, broken away in part, showing my improvement applied to a coin-stacking stamp-machine of the class described.

Fig. 2 is a part sectional elevation of the mechanism shown in Fig. 1, the section being taken on line 2—2 of Fig. 1.

Fig. 3 is a similar sectional view with the latch and guard in their raised positions, 95 the stacking tube being omitted.

Figs. 4 and 5 are respectively a top plan view and a front view of the guard.

As is clearly shown in the drawings the device consists in a coin receptacle or tube 100 1, into which coins are fed by the feeding-in slide 2, which slides back and forth along a base plate 3, which is carried by the frame 4 of the machine.

To prevent the slide 2 from being pushed 105 in far enough to enable it to actuate the stamp-vending mechanism on the return stroke, provided no coin has been deposited on the slide, I provide the stop 5. This stop when down is in the path of travel of the 110

end of slide 2, as shown in Fig. 1, and when raised allows the slide to pass. By means of a beveled tooth 6 adapted to be engaged by the coin, stop 5 is automatically raised 5 clear of the slide when the slide is advanced with a coin in place, as shown in Fig. 2.

Both the stop 5 and the beveled tooth 6 are carried by a latch 7, which is preferably pivotally mounted to frame 4, as at 8. The 10 latch is spring-pressed downwardly by a spring 9, also secured to frame 4.

Beneath the point of the beveled tooth 6, which is carried by the pivoted latch 7, I locate a guard 10 which is in effect a small 15 plate, the upper surface of which bears yieldingly against the point of the tooth 6, being spring-pressed upwardly so that the guard remains in contact with and follows the tooth in its upward movement when the 20 latch is raised.

Guard 10 is carried by an arm 11 which is pivotally mounted as at 12 on the frame 4 of the machine and is spring-pressed upwardly by means of the arm 13 and the 25 spring 14, which is of less strength than the spring 9 of latch 7.

Assuming that there is no coin in the slide 2, if the latch 7 is raised, either accidentally or by intention, the guard plate 10 will follow the upward movement of the beveled tooth 6 and the guard will lie directly in the path of the advancing slide 2, as shown in Fig. 3, so that the slide 2 will strike the 30 guard and be prevented from further inward movement.

Assuming that a coin has been placed in the slide and that the latch 7 has been fraudulently raised, as by means of a wire inserted from outside the machine, a flange 15 or 40 equivalent projection on the guard 10 will engage the advancing edge of the coin and block the slide.

If the coin has been deposited in the slide, and the latch 7 is permitted to operate in 45 its normal manner, the coin and the slide will advance until the forward edge of the coin is above the edge of the guard 10, and the coin will then force its way in between the guard 10 and the point of the tooth 6, 50 raising the latch 7 and the stop 5 and permitting the coin to pass into tube 1.

The slide 2, having thus been permitted to travel its full stroke, will actuate the stamp-vending mechanism on its return 55 stroke, in the manner set forth in my pending application above referred to.

It is thus seen that the guard 10 blocks the forward movement of the slide if the stop-latch 7 has been raised, either by accident or intention. If the slide is pushed 60 forward without carrying a coin, the guard 10 blocks the slide. If a coin has been deposited on the slide, but the latch has been lifted by a wire or otherwise the guard will block the slide.

When the slide is blocked it is prevented from moving to the end of its travel, and as has been heretofore noted, the operating connection between the slide 2 and the stamp vending mechanism is such in this type of 70 machine that the vending mechanism will not operate to deliver a stamp unless the slide has first been pushed in to the extreme end of its travel.

Consequently the guard herein described 75 effectually prevents fraudulent issue of stamps or goods from the vending machine.

Having thus described my invention, what I claim and desire to secure by Letters Patent is:

1. A coin-controlled apparatus comprising a coin receptacle, a feeding-in slide adapted to deliver coins to said receptacle, a locking device comprising a yieldingly movable latch, a beveled tooth carried by said latch, a yieldingly movable guard normally bearing against the end of said tooth and adapted to yield to permit the passage of a coin between the tooth and guard when the latch is in normal position, and adapted to engage said slide to stop its forward movement when the latch is raised; a stop on said latch, normally located in the path of travel of said slide and adapted to lift out of engagement with said slide when said tooth is lifted by a coin passing thereunder.

2. A coin-controlled apparatus comprising in combination, a coin receptacle, a feeding-in slide, a yieldingly movable latch, a stop and a beveled tooth carried by said latch 100 and adapted to engage respectively said slide and a coin carried by said slide, a guard member yieldingly pressed against the end of said tooth and adapted to be moved therewith into the path of travel of 105 said slide, for the purposes set forth.

In testimony whereof, I affix my signature in presence of two witnesses.

RICHARD T. HOSKING.

Witness:

ROY WALLIS,
GEO. B. WILLCOX.
